UNITED STATES PATENT OFFICE.

JOHN A. WEIMER, OF LEBANON, PENNSYLVANIA.

BOGIE-TRUCK FOR RAILWAY-CARS.

SPECIFICATION forming part of Letters Patent No. 717,060, dated December 30, 1902.

Application filed September 4, 1902. Serial No. 122,075. (No model.)

To all whom it may concern:

Be it known that I, JOHN A. WEIMER, a citizen of the United States, residing at Lebanon, in the county of Lebanon and State of Pennsylvania, have invented certain new and useful Improvements in Bogie-Trucks for Railway-Cars; and I do hereby declare the following to be a full, clear, and exact description of the invention, such as will enable others skilled in the art to which it appertains to make and use the same.

My invention relates to railway-cars, and has especial reference to bogie-trucks used in connection therewith on cinder-cars, hot-metal cars, and cars used for other purposes; and it consists in certain improvements in construction, which will be fully disclosed in the following specification and claims.

In the accompanying drawings, which form part of this specification, Figure 1 represents a side elevation of a bogie-truck provided with my improvements; Fig. 2, a front elevation of a section thereof, the coupling being omitted; Fig. 3, a top plan view of the same; Fig. 4, a front elevation of the bolster, partly in section and on a reduced scale; Fig. 5, a vertical transverse section of the same; Fig. 6, a top plan view of the cross or transom member; Fig. 7, a front elevation thereof; Fig. 7^a, an end view of the same; Fig. 8, a top plan and a vertical transverse section of the bearing-plate detached, and Fig. 9 a broken vertical longitudinal section of the bolster and the cross or transom member.

Reference being had to the drawings and the designating characters thereon, 11 indicate the side or lateral members of the truck, connected together by the cross or transom member 2 thereof, said parts being preferably of cast-steel. Said lateral members, unlike their answering or corresponding parts as heretofore constructed, are so made, preferably, as shown particularly in Figs. 1 and 3, that the wheels or their axial centers are adapted to be brought comparatively close together to more readily accommodate the travel of the latter in rounding sharp curves in the track. This is provided for mainly by the arrangement and construction of the cross or transom member 2 and the manner of effecting connection therebetween and said lateral members at points in a plane above said

wheels and within prescribed limits, as will be presently explained. Said lateral members are suitably made to receive the journal boxes or bearings of the wheel-axles and the usual springs or cushions for said journals, preferably as shown. Said lateral members are, however, widened centrally, as at 11, at their upper laterally-extended edges or 55 surfaces for a purpose later described. Said cross or transom member, preferably centrally downwardly-curved in its upper surface, as disclosed particularly in Figs. 7 and 9, is rectangular in its general outline in plan, 60 with narrow arcuate portions or elevations 22 short distances inwardly from its ends and projecting somewhat beyond both the forward and rear edges of the upper surface of said transom member after the fashion of arcs 65 of a fifth-wheel of a vehicle, the object of which will appear presently. Beyond said elevations or arcuate portions 22 said transom member is provided with plate-like extensions 44, having themselves downwardly-extending or pendent projections or flanges 70 75. The straight or vertical end walls or surfaces 5 of said transom member engage or fit against the inner sides of the lateral members 11, while the plate-like lateral portions or 80 extensions 4 overlie or rest upon the top widened portions 11 of said lateral members, and the pendent portions or flanges 44 fit against the outer edges or surfaces of said widened portions. Said plate-like extensions are provided with, preferably, rows of holes 6, through which are inserted bolts 7, passing through registering holes produced in the widened portions 11 of said lateral members and nutted thereunder, effecting the securing together of 85 90 said parts, as shown. Through holes also produced in the lower end portions or surfaces 5 of said transom member are inserted securing-bolts 88, passing through said lateral members, additionally fastening said parts together. Said transom member 2 below its upper rectangular surface is preferably of the construction shown, having a vertical web 33, lozenge or double-Y shaped, as shown in dotted lines in Fig. 6, with the widened separated portion central thereof and tapering or converging from the longitudinal center of the transom to and integral with the vertical lower end portions 5, securing strength com- 95 100

2
bined with lightness. Said transom member by reason of its construction reduces the number of fastening-bolts to the minimum, and yet is strongly and firmly held in place 5 to the lateral members. Also the converging or tapering of the web of said transom member toward its lower end securing portions 5 provides, in connection with the overlying end securing plates 4, for arranging the car-
10 wheels comparatively close together, as above noted and for the purpose aforesaid. Also bolted or riveted centrally to the upper surface of said transom member 2 is an annularly-grooved circular plate or table 10, and
15 above said member or part is arranged or disposed the bolster 12, having annular pendent ribs or rings 13 at its center upon the lower surface engaging, as shown, the correspondingly-grooved surface of said table or
20 plate. Said bolster is held revolutely in such position by a "king-bolt" 14, passing therethrough and through said transom member, it being suitably headed in a depression or enlargement of the opening in said member
25 receiving it and held at its lower end by a pin inserted transversely through said bolt below said member. Said bolster may also be equipped with a preferably removable rack 15, as in employing the truck or invention
30 in connection with a car of the type or class for conveying molten or liquid "cinder." Although herein shown and described as applied to this particular class of cars, said truck is equally adapted for use, as is
35 apparent, with any character of car, as above noted. Extending forwardly from and forming, preferably, a common casting with said bolster is a sleeve or "pocket" 16, adapted to suitably receive and permit of the proper
40 cushioning therein of the draw bar or head 17 for connecting or coupling the truck to any suitable means or motor for its movement, as may be required. Suitable manipulating means or lever arrangement 18, sup-
45 ported, preferably, as shown or otherwise, may be employed for adjusting or disposing said coupling in operatively connecting up the same with the motor. A casting or cross-bar 19, fastened or bolted to, and connecting
50 together, the lateral or side members 11 near their forward ends, also serves to support the forwardly-extending draw bar or head 16 with its coupling, as greatly desired for that purpose to relieve the preponderant weight
55 of said parts, being otherwise unsupported beyond the bolster. Said cross-bar or casting is suitably curved upwardly from under the draw-bar 16 toward or at its end portions, as shown particularly in Fig. 2, and secured
60 or bolted, as at 20, to the top surfaces of the lateral members near their forward ends, as also seen in said figure and Fig. 3. Said support or cross-bar 19 has cast or integral with its upper surface strengthening rib-like portions or elevations 21, preferably extending
65 from points upon each side of and short distances away from its center and clear to the

ends of said cross-bar, said bar being preferably rectangular in its general contour and rectilinear or flat, especially where it forms 70 a support or rest for the draw bar or head, as seen in Fig. 2.

In the organization or carrying into effect my invention I employ only three castings and, as before intimated, reduce the number 75 of bolts for connecting the parts together.

Having thus fully described my invention, what I claim, and desire to secure by Letters Patent, is—

1. In a car or bogie truck, the combination 80 of side members, a cross or transom member connecting the side members and having end or lateral securing extensions in the plane of said transom member, and provided with vertical end members, said extensions overlying 85 and engaging the upper edge or surface of said side members, and said vertical members engaging one side of said side members.

2. In a car or bogie truck, the combination 90 of side members having upper central widened portions, a transom member having end or lateral securing extensions and pendent terminals, and vertical end members, and means for fastening said lateral securing extensions to said widened portions, and said 95 end members to one side of said side members.

3. In a car or bogie truck, side members, in combination with a transom member connecting the side members and having end or lateral securing extensions provided with downwardly-extending terminals, the former overlying the upper surfaces of said side members, and the latter engaging said members laterally, and said transom member also having vertical end-securing portions inward 105 from said extensions.

4. In a car or bogie truck, side members, in combination with a transom member connecting the side members and having end or lateral securing extensions provided with downwardly-extending terminals, the former overlying the upper surfaces of said side members, and the latter engaging said members laterally, said transom member also having vertical end-securing portions engaging 115 said side members, and a bolster revolutely mounted upon said transom member and bearing upon arc-shaped elevations on the last-named member.

5. In a car or bogie truck, side members, in 120 combination with a transom member provided with lateral securing extensions, and vertical end members, and a vertical web separated laterally in the center, converging toward each end and connected to said end members. 125

6. In a car or bogie truck, a transom member having a centrally-depressed upper portion or surface, a bolster adapted to rest in the depression and revolutely mounted upon said surface, said bolster having a forwardly-extending integral pocket or sleeve adapted to receive a coupling.

7. In a car or bogie truck, side members, in combination with a transom member con-

nected to said side members, a bolster mounted upon said transom member and having a forwardly-extending pocket or sleeve to receive a draw bar or head, and a cross-bar connected to said side members near their forward ends and adapted to afford a support or rest for said pocket or sleeve.

5 8. In a car or bogie truck, side members, in combination with a transom member connecting said side members, a bolster mounted upon said transom member and having a forwardly-extending draw-head carrying pocket

or sleeve, and a cross-bar connected to said side members near their forward ends, and having a central depressed portion arranged 15 under said pocket or sleeve, and upwardly-curved rib-strengthened end portions secured or bolted to said side members.

In testimony whereof I affix my signature in presence of two witnesses.

JOHN A. WEIMER.
